MULTIPLEX SIGNAL-TRANSLATING
SYSTEM

John C. Wilson, Bayside, N. Y., assignor to Hazeltine Corporation, a corporation of Delaware

Application May 28, 1940, Serial No. 337,569

13 Claims.

(Cl. 179—15)

This invention relates to a multiplex signal-translating system in which a plurality of signal-input channels are successively operatively coupled through a signal-transmission channel to a plurality of signal-output channels in such a way that the signal-transmission channel is used at any given instant only for connecting one of the signal-input channels to its corresponding signal-output channel.

Such a multiplex signal-translating system is 10 commonly referred to as a "shared-time" multiplex system, to distinguish it from the more widely-used "shared-frequency" system in which the frequency range of the signal-transmission channel is divided into sub-ranges by filters, each sub-range being continuously available for connection between a pair of signal-input and signal-output channels.

The above-mentioned type of multiplex signal-translating system has been embodied in a number of types of prior art apparatus. For instance, the transmission channel has comprised a channel having a wide transmission pass band and the system has been used to couple several corresponding input and output channels which translate signals of a frequency range which is narrow with respect to the pass band of the transmission channel. Such an arrangement has been used in telephone and telegraph systems so that a single transmission line or channel can be 30 utilized to transmit a plurality of different telephonic or telegraphic signals.

Synchronously-operating cathode-ray tube switching arrangements have been utilized in the input and output channels of certain of the prior art systems of the type described in order successively and cyclically to couple only each of the signal-input channels at any instant with its corresponding signal-output channel through the transmission channel. Such switching arrangements must be operated at a very high frequency, that is, a frequency which is higher than the frequency of the highest-frequency signal component to be transmitted, so that several portions of each cycle of such highest-frequency signal component to be transmitted are represented in the transmission channel. If this condition is met and a sufficient number of these portions are transmitted for each cycle of the highest-frequency signal component to be transmitted, the fidelity of reception is not unduly impaired and the arrangement has the advantage of allowing the simultaneous transmission of a plurality of different signals over a single transmission channel.

However, in prior art systems of the type mentioned, it has been the practice to allot a given fraction of the cycle of operation of the synchronous switching means to each signal which 5 the transmission channel and its associated synchronous switching arrangement is capable of transmitting so that the number of separate signals which may be transmitted over such an arrangement is limited by the fidelity of transmission required. The fidelity is determined by the number of times a given input channel and its corresponding output channel are connected together through the transmission channel during the transmission of a cycle of the highest-frequency component of the signal being translated. For instance, the limiting number of separate signals which may be transmitted over a given transmission channel may be 100. This means that, in a telephone system, for instance, one 15 transmission channel must be provided for each 100 subscribers. However, all channels of such an arrangement are very infrequently, or never, used simultaneously; in fact, it is usually found in practice that, out of a given number of signal-input channels, the probability is that only a small percentage thereof will be used simultaneously. This means that if a given transmission line or channel is capable of transmitting 100 separate signals simultaneously, it would 20 serve for several hundred subscribers or signal-input channels providing only those being used were actually connected to the synchronous transmitting arrangement at a given instant. However, this operation is not, in general, practical due to the large number of switches and the complexity of the switching operations required. It is, therefore, particularly desirable to provide an arrangement of the general type described in which a large number of input and 25 output channels may be coupled to the synchronous switching arrangement and in which only the corresponding input and output channels which are in actual use share the total available operating time on the transmission channel; that is, the synchronous switching cycle is 30 divided equally only between such channels in use.

It is an object of the invention, therefore, to 35 provide an improved multiplex signal-translating system of the general type under discussion.

It is another object of the invention to provide 40 a multiplex signal-translating system by which a plurality of signal-input channels and corresponding signal-output channels, only a few of 45 which are in operation during a given interval,

may be successively and cyclically coupled through a transmission channel in such a way that only the corresponding input and output channels which are in use during any given interval share the time on the transmission channel during that interval.

In accordance with the invention, a multiplex signal-translating system comprises a signal-transmission channel, a plurality of signal-input channels, and a plurality of corresponding signal-output channels. The system includes means for cyclically simultaneously connecting and disconnecting the signal-input channels and corresponding signal-output channels to the signal-transmission channel in a predetermined sequence and at a frequency which is higher than that of the highest-frequency signal component to be transmitted from any of the signal-input channels over the signal-transmission channel. Means are further provided for controlling the fraction of an operating cycle of the first-named means that any particular signal-input channel which is in use and its corresponding signal-output channel are connected together through the signal-transmission channel inversely in accordance with the number of signal-input channels which are in use during the operating cycle.

As used in this specification, the term "frequency which is higher than that of the highest-frequency signal component to be transmitted" has reference to the frequency of the highest modulation frequency in case a modulated-carrier signal is transmitted and in any case has reference to the highest-frequency signal which is transmitted and reproduced.

Synchronously-operating cathode-ray tube switching arrangements have been utilized in the input and output channels of certain of the prior art systems of the "shared-time" type in order successively and cyclically to couple only each of the signal-input channels at any instant with its corresponding signal-output channel through the transmission channel. The present invention is concerned with systems in which such switching arrangements are operated at a very high rate, that is, a rate which is higher than the frequency of the highest-frequency signal component to be reproduced, so that on the average at least some portion of each cycle of such highest-frequency signal component to be reproduced is represented in the transmission channel. If this condition is met the fidelity of reception is not unduly impaired and the arrangement has the advantage of allowing the simultaneous transmission of a plurality of different signals over a single transmission channel.

For a better understanding of the present invention, together with other and further objects thereof, reference is had to the following description taken in connection with the accompanying drawings, and its scope will be pointed out in the appended claims.

Fig. 1 of the drawings is a circuit diagram, partly schematic, of a complete multiplex signal-translating system embodying the invention, while Figs. 2a-5, inclusive, comprise graphs used to explain certain of the operating conditions of the system of Fig. 1.

Referring now more particularly to Fig. 1 of the drawings, there is shown therein a multiplex signal-translating system comprising a signal-transmission channel which may be either a radio or wire channel and is represented by lines 10, 10; a plurality of signal-input channels, represented,

respectively, by single conductors 11-18, inclusive, and a common ground return; and a plurality of corresponding signal-output channels, represented by the single conductors 19-26, inclusive, and a common ground return. Means are provided for successively and cyclically simultaneously connecting and simultaneously disconnecting the signal-input channels 11-18, inclusive, and corresponding signal-output channels 19-26, inclusive, to the signal-transmission channel 10, 10 at a predetermined frequency which is higher than that of the highest-frequency signal component to be transmitted from any of the signal-input channels 11-18, inclusive, over the signal-transmission channel 10, 10 to corresponding signal-output channels 19-26, inclusive. This means comprises a cathode-ray tube 27, utilized as a multiple-circuit switching device at the signal-input end of the transmission channel 10, 10, and a similarly-connected cathode-ray tube 28, utilized as a multiple-circuit switching device at the output end of the transmission channel 10, 10. Each of the cathode-ray tubes 27 and 28 comprises, in the order named, a conventional electron gun which may consist of a cathode 30 and an accelerating anode 31, vertical deflecting plates 32, 33, horizontal deflecting plates 34, 35, a collector electrode 36, and a plurality of rectangular target electrodes, of which two are identified as 37, 38, the letters "a" and "b" being associated with the reference numerals identifying elements of tubes 27 and 28, respectively. Means, to be hereinafter described in detail, are provided for deflecting the beams of tubes 27, 28 to scan their respective target electrodes, including electrodes 37 and 38, synchronously in the two cathode-ray tubes at a frequency which is higher than that of the highest-frequency signal component to be transmitted from any of the signal-input channels over the signal-transmission channel.

Input channels 14 and 17 only are illustrated as being connected, respectively, to target electrodes 37a and 38a of cathode-ray tube 27, although it will be understood that any practicable number of target electrodes can be utilized in cathode-ray tube 27, each of which is operatively connected to an input channel of the type represented by conductors 11-18, inclusive, only the two target electrodes being shown operatively connected for the purposes of illustration herein. The signal-input channel 14 is connected to target electrode 37a through an amplifier 40 while signal-input channel 17 is similarly coupled to target electrode 38a through an amplifier 41, this latter channel being shown in dotted lines for the sake of clarity.

The cathode-ray tube switching device 28 comprises also a control grid 42b and output signals, derived from collector electrode 36a of cathode-ray tube 27, are translated through an amplifier 44, the signal-transmission channel 10, 10, and an amplifier 45 to the control grid of cathode-ray tube 28. A signal-translating device 46, corresponding to signal-input channel 14, is coupled to target electrode 37b of cathode-ray tube 28, while a signal-translating device 47, corresponding to signal-input channel 17, is correspondingly coupled to target electrode 38b of cathode-ray tube 28. Switches 6, 7, 8, and 9 are provided so that any signal-input channel and its corresponding signal-output channel may be permanently disconnected from the system.

Assuming that the target electrodes of cathode-ray tubes 27 and 28 are synchronously scanned by the cathode-ray beams developed

therein. the system so far described is conventional and its operation will be well understood by those skilled in the art. Specifically, each input circuit is connected during predetermined intervals as the successive targets of tubes 27 and 28 are scanned through transmission line 10, 10 with its corresponding output circuit. Each portion of a signal which is translated by the transmission channel 10, 10 is effective to vary the electron stream of tube 28 in accordance with the translated signals and, therefore, to vary the output derived from the target electrodes of the tube in accordance with the translated signals. If the frequency of the operating cycle of the synchronous connecting and disconnecting means is very high and the pass band of the channel 10, 10 is adequate, the fidelity of transmission of any given signal is not unduly materially impaired.

Coming now to the portion of the system of Fig. 1 involving the present invention, there is provided means for controlling the fraction of an operating cycle of the synchronous switching means that any particular signal-input channel which is in use and its corresponding signal-output channel are connected together through the signal-transmission channel 10, 10 inversely in accordance with the number of signal-input channels which are in use at the time. That is, an arrangement is provided whereby only those signal-input channels and their corresponding signal-output channels which are being utilized to translate a conversation or other signal are caused to share the effective portion of the operating cycle.

The system comprises means for scanning the target electrodes of each of cathode-ray tubes 27 and 28 at a very high frequency in the absence of any signal input to the transmission line 10, 10 and for causing the scanning of such target electrodes to which signals are applied to be very materially retarded in order that substantially the total time of a scanning cycle of the synchronous switching means be devoted only to those target electrodes which are connected to signal-input channels in use. In order to provide this type of scanning, there is provided a saw-tooth scanning oscillator, including condenser 56 adapted to be charged and discharged, to provide scanning potentials in the horizontal direction. In order to charge condenser 56 at a relatively slow rate to provide horizontal deflection for the cathode-ray scanning beam of tube 27, there is provided a vacuum tube 62 through the anode-cathode circuit of which condenser 56 is coupled to the high-voltage source 60. A suitable screen-voltage operating potential for vacuum tube 62 is provided by means of voltage-dividing resistor 63 coupled across the high-voltage source 60. In order to discharge condenser 56 after the voltage thereof has risen to a predetermined value, there is provided a tube 64, which may be a gas-filled tube or a tube suitably coupled to provide regeneration, having its anode-cathode electrodes coupled across condenser 56 and having a control grid to which is applied a suitable negative bias from source 65. The arrangement is such that, for a given conductance of vacuum tube 62, the condenser 56 is relatively slowly charged to a predetermined voltage, as represented by dotted line 74 of Fig. 2a, through vacuum tube 62, as indicated by charging line 73 of Fig. 2a, and is rapidly discharged through tube 64, as indicated by line 75 of Fig. 2a, after the potential of condenser 56

has risen sufficiently to cause tube 64 to become conductive. This cycle is repeated to provide saw-tooth scanning voltages for scanning tube 27 in the horizontal direction.

8 In order to scan cathode-ray tube 27 in the vertical direction, there is provided a "ratchet" scanning-potential generator comprising a condenser 66 and a resistor 67 to form a differentiating circuit such that the high rate of change of voltage, corresponding to the rapid discharge of condenser 58 through tube 64 causes a pulse voltage to appear across the resistor 67. This pulse voltage across resistor 67 is applied to the input circuit of a vacuum tube 69 which has its anode-cathode circuit included in the charging circuit of a condenser 58. A suitable bias is provided for tube 69 by means of source 68 which, in the absence of such a voltage pulse, biases the tube 69 to cutoff. The discharge circuit of condenser 58 includes a gas-filled tube 70 having its anode-cathode electrodes coupled across condenser 58 and having a control electrode so biased that the tube becomes conductive and effective to discharge condenser 58 only after the voltage of condenser 58 has risen to a predetermined value.

It is thus seen that each time condenser 58 is discharged, a voltage pulse is applied to the input circuit of vacuum tube 69 so that tube 69 is caused to be conductive for a predetermined interval to charge condenser 58 a predetermined increment or step, for instance, the step 76 of Fig. 2b, which represents the voltage-time characteristic of the condenser 58 of the ratchet horizontal scanning oscillator. The increment of charging voltage of condenser 58 during each of these charging intervals is just sufficient to step the scanning beams of cathode-ray tube 27 from one horizontal row of target electrodes to the next succeeding lower row of target electrodes.

In order to provide a suitable deflection, in the absence of potentials on condensers 56 and 58, so that the beam of cathode-ray tube 27 is on the first target of the first row of targets, there is provided an initial deflection bias for the horizontal scanning electrodes 34a, 35a by means of resistor 59 coupled across the high-voltage source 60 and having a tap thereon coupled to scanning plate 35a of tube 27, while a similar bias resistor 61 is provided for plate 32a of tube 27. The circuit is thus proportioned so that the target electrodes of tube 27 are scanned in a cyclical order in a series of horizontal lines. Scanning circuits similar to that just described have been proposed for velocity-modulated television systems, one such circuit being described in the Journal of the Institution of Electrical Engineers (London) in an article of L. H. Bedford and O. S. Puckle entitled "A velocity-modulation television system," vol. 75, No. 451, pp. 63-82.

It will be understood that cathode-ray tube 28 at the receiving station is similarly scanned and, for this purpose, the scanning potential applied to scanning plates 34a, 35a of tube 27 is transmitted over a channel or line 34' and applied to the input circuit of a controlled scanner 71. It will be understood that suitable initial biasing potentials are provided for the scanning plates 32b and 35b of cathode-ray tube 28 in a manner similar to that described for cathode-ray tube 27. It will also be understood that the portion of the system of Fig. 1 included within the dotted line 72 is duplicated in the controlled scanner 71 in order to provide suit-

able scanning potentials for application to plates 32b, 33b of cathode-ray tube 28.

Reference is made to the graphs of Figs. 2a and 2b for an explanation of the scanning or operating cycle of cathode-ray tubes 27 and 28 under the conditions when none of the signal-input channels is in use. Starting at time t_0 , it is seen that condenser 56 is slowly charged through the vacuum tube 62, as represented by the charging line 73, until its potential rises to that at which tube 64 becomes conductive, as represented by the dotted line 74 of Fig. 2a. At this point in the cycle, condenser 56 is rapidly discharged as represented by the discharge line 75 and this cycle is repeated indefinitely. During the time of discharge of condenser 56, as represented by the discharge line 75, a pulse voltage is applied to the input circuit of tube 69 through the differentiating circuit 66, 67, thereby to cause tube 69 to become conductive and partially to charge condenser 58 as represented by the voltage step 76 of Fig. 2b. These steps are repeated during each discharge period of condenser 56 until the discharge potential of condenser 58, represented by the dotted line 77, is reached after which condenser 58 is discharged through tube 70, which is so biased that it becomes conductive when its anode-cathode potential reaches that represented by dotted line 77. The circuit is so proportioned that the discharge potential, represented by dotted line 77, is obtained during the discharge period of condenser 56 following the scanning of the last line of the target electrodes of cathode-ray tube 27.

In order to cause the scanning beam of cathode-ray tubes 27 and 28 to be delayed for a large fraction of a cycle of the synchronous operation thereof only on those of the target electrodes of the tube corresponding to signal-input channels which are in use, there is provided an additional cathode-ray tube 50 for the purpose of providing a control-signal output which varies in accordance with the pattern represented by the particular target electrodes of the cathode-ray tube 27 which are being energized through one of signal-input channels 11-18, inclusive. The cathode-ray tube 50 is generally similar to cathode-ray tube 27 and similar circuit elements have identical reference numerals with the added letter "c". The scanning plates of cathode-ray tube 50 are connected in parallel with those of tube 27. In order to energize target 37c of cathode-ray tube 50 simultaneously with the transmission of a signal through target 31a of cathode-ray tube 27, there is provided a rectifier 51, coupled to the output circuit of amplifier 40 and, in turn, having its output circuit coupled through a limiter 52 to target electrode 37c of cathode-ray tube 50. Similarly, there is provided for target electrode 38c of cathode-ray tube 50, a rectifier 54 having an input circuit coupled to the output circuit of amplifier 41 and having its output circuit coupled through a limiter 55 to target electrode 38c of cathode-ray tube 50.

There is provided an arrangement for deriving an output from cathode-ray tube 50 to reduce the conductance of vacuum tube 62 during the interval when there is being scanned a target energized from a signal-input channel in use, thereby to retard the charging of condenser 56 instantaneously to retard the rate of scanning of such target in both tubes 27 and 28. For this purpose, there is provided an amplifier 78 which is designed to be quickly responsive and having

its input circuit coupled to a load resistor 36' in the circuit of the collector electrode 36c of tube 50 and having its output circuit coupled to a control electrode of vacuum tube 62. Tube 50 is, therefore, scanned synchronously with the scanning of tube 27 and the rate at which electrons are collected at electrode 36c of tube 50 at any instant depends upon the potential of the target electrode being scanned. For each energized target of cathode-ray tube 50 which is scanned, a negative potential pulse is, therefore, developed across the load resistor 36' of collector electrode 36c of tube 50 and applied to amplifier 78 and the amplifier is so proportioned that there is also derived therefrom a negative potential pulse effective to reduce the conductance of vacuum tube 62 for the duration of the pulse, thereby to retard the charging of condenser 56.

In order to explain the effect of control tube 50 and its associated apparatus on the circuit of Fig. 1, reference is made to Figs. 3a and 3b. It is here assumed that only target electrode 37c or the second target electrode of the first row of targets of each of cathode-ray tubes 27, 28, and 50 is energized, which means that only the signal-input and output channels which are connected through transmission line 10, 10 and through these targets are energized by an input signal for translation. Under these conditions, the scanning potentials derived from the horizontal scanning oscillator including condenser 56 and from the vertical scanning oscillator including condenser 58 are represented by the curves of Figs. 3a and 3b, respectively. It is thus seen that at the time t_0 , which corresponds to the beginning of a scanning cycle, the first target of the first row is scanned very rapidly and at the same rate as obtained under the condition of operation illustrated by the curve of Fig. 2a. Therefore, during the time of scanning of the first target of the first row, the voltage across condenser 56 rises in a relatively short time, as represented by charging line 79, approximately to one-third the maximum scanning amplitude represented by dotted line 74, which is the voltage required to cause tube 64 to become conductive and discharge condenser 56. Thereafter, the second target of the first row, or target 37c, which is the one assumed to be in use, is scanned and, during this interval, a signal output is derived from collector electrode 36c of tube 50 which is applied to tube 62 through amplifier 78 materially to lower its conductance, thereby to reduce the charging rate of condenser 56, as illustrated by the charging line 80. This condition obtains until the voltage across condenser 56 has reached approximately two-thirds the maximum scanning voltage represented by line 74; when the scanning of the target connected to the input channel in use is completed, the control bias derived from the collector electrode of tube 50 falls and the charging rate is again increased to its maximum value as represented by the charging line 81. The remainder of the scanning cycle is substantially identical to that described with reference to Fig. 2a. The corresponding ratchet voltage of condenser 58 is illustrated in Fig. 3b. In the arrangement described above, it is assumed that modulated-carrier signals are to be translated from the input channels to the output channels, for the reason that, under this condition of operation, a potential always exists on the target electrode of cathode-ray tube 50 corresponding to a particular input channel whenever that input channel is being utilized to translate a signal,

irrespective of whether a modulation signal is being transmitted at the particular instant. It will be understood, however, that applicant's invention is not limited to arrangements in which modulated-carrier signals are translated.

It is seen, therefore, that applicant's system is effective to cause the greatest part of the operating cycle of the synchronous switching means to be devoted to the scanning of the second target of the first row, which is the only target connected to a signal-input channel in use.

In Figs. 4a and 4b there are shown, respectively, curves which correspond to those of Figs. 3a and 3b under the conditions that the signal-input channels are in use which are connected to the second target of the first row, the first target of the third row, and the last target of the fourth row. Under these conditions, it is seen that the charging line 82 represents the charging of condenser 56 during the time that the first target of the first row is rapidly scanned, the charging line 83 corresponds to the relatively slow scanning of the second target of the first row, and the line 84 corresponds to the rapid scanning of the third target of the first row. After this target has been scanned, the discharge voltage 74 of condenser 56 is reached and the tube 64 becomes conductive to discharge condenser 56 as illustrated by the discharge line 85. The charging line of condenser 56 during the scanning of the targets of the second row, none of which is assumed to be energized, is illustrated by the charging line 86 which is followed by the discharge of condenser 56 as represented by the line 87. The relatively slow charging of condenser 56 during the scanning of the first target of the third row is represented by the charging line 88 and the rapid charging of condenser 56 during the scanning of the second and third targets of the third row is represented by the charging line 89, after which condenser 56 is again discharged as represented by the line 90. The rapid charging of condenser 56 during the scanning of the first and second targets of the fourth row is represented by the charging line 91, and the relatively slow charging during the scanning of the last target of the last row is represented by the line 92, after which the cycle repeats, beginning at time t_1 .

It is thus seen that applicant's system comprises means for controlling the fraction of an operating cycle that any particular signal-input channel which is in use and its corresponding signal-output channel are connected together through the transmission channel inversely in accordance with the number of signal-input channels which are in use and that means are provided to cause only the particular signal-input channels and their corresponding signal-output channels which are in use during an operating cycle to share the effective portion of the operating cycle. As so far described, this is accomplished by extending the time of each operating cycle in accordance with the number of signal-input channels which are in use. Furthermore, it is seen that the sum of all the operating-cycle fractions corresponding to input circuits which are in use is a substantial part of the operating cycle and preferably the arrangement is so designed that the sum of all said fractions is substantially the whole of the operating cycle.

From the operating characteristics of Figs. 3a, 3b and 4a, 4b, it is seen that the period of a scanning cycle in the system, as so far described, varies in accordance with the number of input

channels which are energized during the operating cycle and that the time of each operating cycle is extended in accordance with the number of signal-input channels which are in use.

5 This variation in the period of the scanning cycle may be undesirable under certain conditions of operation and, for the purpose of maintaining the period of each operating cycle substantially constant while effecting an operation generally 10 in accordance with that described above, there may be provided in addition an arrangement for controlling the gain of amplifier 78 inversely in accordance with the number of signal-input channels which are in use. For this purpose, there is provided a gain-control means 93 having an input circuit coupled to collector electrode 36_c of cathode-ray tube 50 and having an output circuit from which is derived a potential utilized to control the gain of amplifier 78. The gain-control means 93 comprises a vacuum-tube amplifier 94 having an input circuit coupled to collector electrode 36_c of tube 50 and an output circuit coupled to the input electrodes of a vacuum tube 95 included in a "counter" circuit. The output circuit of tube 95 comprises a load resistor 96 and a source 97 of unidirectional operating voltage coupled in series. There is also coupled across the series combination a series-connected diode 98 and condenser 100. A resistor 99 is connected between a terminal common to diode 98 and condenser 100 and a tap on source 97. The voltage across condenser 100 is utilized to control the gain of amplifier 78, being applied thereto through a suitable filter.

35 In considering the operation of the circuit of gain-control means 93, it will be assumed that vacuum tube 95 is so biased as to become conductive only when a target electrode of cathode-ray tube 50 is being scanned which has a signal applied thereto. It will thus be seen that condenser 100 is charged slightly positively from the source 97 during the time when tube 95 is non-conductive through the charging circuit including resistor 99. Each time tube 95 becomes conductive, condenser 100 is partially discharged through diode 98. The degree to which condenser 100 is discharged, therefore, depends upon the number of targets which are in use. Therefore, under each condition of operation of the transmitting arrangement described, the potential which exists across condenser 100 varies in accordance with the number of target electrodes of cathode-ray tube 50 which are connected to signal-input channels in use. This potential is applied to one or more of the control grids of vacuum tubes in amplifier 78 to decrease their amplification in accordance with the magnitude of the control voltage in a manner well understood in the art.

60 55 In order to explain the operation of the system as a whole, taking into account the operation of the gain-control arrangement 93, reference is made to the curve of Fig. 5 which is somewhat similar to the curve of Fig. 4a, the general shape of the curve being the same and the only difference being that the over-all period of the scanning cycle t_0-t_1 is materially reduced by the operation of the gain-control means 93, and is maintained within relatively narrow limits for a wide range of variation in the number of signal-input channels in use. Thus, considering again the conditions of operation assumed in describing the system with reference to Figs. 3a and 4a, it is seen that the period of an operating cycle is materially increased, with respect to that

when only one of the signal-input channels is in use, when three target electrodes are energized, as illustrated by the curve of Fig. 4a; that is, the period of the scanning cycle represented by the curve of Fig. 4a is materially longer than that represented by the curve of Fig. 3a. Under the operation of the gain-control arrangement 93, however, it is seen that the period of a complete scanning cycle when three target electrodes are energized is materially decreased, as illustrated by the curve of Fig. 5. Therefore, the effect of the gain-control arrangement is to cause the period of an operating cycle, when the signal-input channels connected to a plurality of control electrodes are in use, to approach, or to become substantially equal to, the period of a scanning cycle when only one signal-input channel is in use.

While, in the arrangement described, the scanning beams of tubes 27, 28, and 50 are caused to scan more slowly the target electrodes corresponding to signal-input and signal-output channels actually in use, that is, which are energized, by means of potentials derived from the channels in use, it will be understood that the invention is not limited to such an arrangement but that the speed of scanning of the several target electrodes can be controlled in response to any suitable operating condition of the system.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A multiplex signal-translating system comprising, a signal-transmission channel, a plurality of signal-input channels, a plurality of corresponding signal-output channels, means for cyclically simultaneously connecting and simultaneously disconnecting said signal-input channels and corresponding signal-output channels to said signal-transmission channel in a predetermined sequence and at a frequency which is higher than that of the highest-frequency signal component to be transmitted from any of said signal-input channels over said signal-transmission channel, and means for controlling the fraction of an operating cycle of said first-named means that any particular signal-input channel which is in use and its corresponding signal-output channel are connected together through said signal-transmission channel inversely in accordance with the number of signal-input channels which are in use during said operating cycle.

2. A modulated-carrier signal-translating system comprising, a modulated-carrier signal-transmission channel, a plurality of modulated-carrier signal-input channels, a plurality of corresponding modulated-carrier signal-output channels, means for cyclically simultaneously connecting and simultaneously disconnecting said signal-input channels and corresponding signal-output channels to said signal-transmission channel in a predetermined sequence and at a frequency which is higher than that of the highest modulation-frequency signal component to be transmitted from any of said signal-input channels over said signal-transmission channel, and means for controlling the fraction of an operating cycle of said first-named means that

any particular signal-input channel which is in use and its corresponding signal-output channel are connected together through said signal-transmission channel inversely in accordance with the number of signal-input channels which are in use during said operating cycle.

3. A multiplex signal-translating system comprising, a signal-transmission channel, a plurality of signal-input channels, a plurality of corresponding signal-output channels, means for cyclically simultaneously connecting and simultaneously disconnecting said signal-input channels and corresponding signal-output channels to said signal-transmission channel in a predetermined sequence and at a frequency which is higher than that of the highest-frequency signal component to be transmitted from any of said signal-input channels over said signal-transmission channel, and means for controlling the fraction of an operating cycle of said first-named means that any particular signal-input channel which is in use and its corresponding signal-output channel are connected together through said signal-transmission channel inversely in accordance with the number of signal-input channels which are energized during said operating cycle and for maintaining the sum of all said fractions corresponding to signal-input circuits which are in use during said operating cycle a substantial part of the operating cycle.

4. A signal-translating system comprising, a signal-transmission channel, a plurality of signal-input channels, a plurality of corresponding signal-output channels, means for cyclically simultaneously connecting and simultaneously disconnecting said signal-input channels and corresponding signal-output channels to said signal-transmission channel in a predetermined sequence and at a frequency which is higher than that of the highest-frequency signal component to be transmitted from any of said signal-input channels over said signal-transmission channel, and means for controlling the fraction of an operating cycle of said first-named means that any particular signal-input channel which is in use and its corresponding signal-output channel are connected together through said signal-transmission channel inversely in accordance with the number of signal-input channels which are energized during said operating cycle and for maintaining the sum of all said fractions corresponding to signal-input circuits which are in use during said operating cycle a major portion of the operating cycle.

5. A multiplex signal-translating system comprising, a signal-transmission channel, a plurality of signal-input channels, a plurality of corresponding signal-output channels, means including synchronously-scanned cathode-ray tubes for cyclically simultaneously connecting and simultaneously disconnecting said signal-input channels and corresponding signal-output channels to said signal-transmission channel in a predetermined sequence and at a frequency which is higher than that of the highest-frequency signal component to be transmitted from any of said signal-input channels over said signal-transmission channel, and means for controlling the fraction of an operating cycle of said first-named means that any particular signal-input channel which is in use and its corresponding signal-output channel are connected together through said signal-transmission channel inversely in accordance with the number of

signal-input channels which are in use during said operating cycle.

6. A multiplex signal-translating system comprising, a signal-transmission channel, a plurality of signal-input channels, a plurality of corresponding signal-output channels, a cathode-ray tube adapted to be connected with said signal-input channels, a cathode-ray tube adapted to be connected with said signal-output channels, means including said cathode-ray tubes and means for synchronously scanning said tubes for cyclically simultaneously connecting and simultaneously disconnecting said signal-input channels and corresponding signal-output channels to said signal-transmission channel in a predetermined sequence and at a frequency which is higher than that of the highest-frequency signal component to be transmitted from any of said signal-input channels over said signal-transmission channel, and means for controlling said scanning means to control the fraction of an operating cycle of said first-named means that any particular signal-input channel which is in use and its corresponding signal-output channel are connected together through said signal-transmission channel inversely in accordance with the number of signal-input channels which are energized during said operating cycle.

7. A multiplex signal-translating system comprising, a signal-transmission channel, a plurality of signal-input channels, a plurality of corresponding signal-output channels, a cathode-ray tube adapted to be connected with said input channels, a cathode-ray tube adapted to be connected with said output channels, means including said cathode-ray tubes and means for synchronously scanning said tubes for cyclically simultaneously connecting and simultaneously disconnecting said input channels and corresponding signal-output channels to said signal-transmission channel in a predetermined sequence and at a frequency which is higher than that of the highest-frequency signal component to be transmitted from any of said signal-input channels over said signal-transmission channel, and means for instantaneously retarding the rate of scanning, only during the period said tubes are operative to connect a signal-input channel which is in use with said signal-transmission channel, whereby the fraction of an operating cycle of said first-named means that any particular signal-input channel which is in use and its corresponding signal-output channel are connected together through said signal-transmission channel is controlled inversely in accordance with the number of signal-input channels which are in use during said operating cycle.

8. A multiplex signal-translating system comprising, a signal-transmission channel, a plurality of signal-input channels, a plurality of corresponding signal-output channels, means comprising a condenser and means for charging and discharging said condenser for cyclically simultaneously connecting and simultaneously disconnecting said signal-input channels and corresponding signal-output channels to said signal-transmission channel in a predetermined sequence and at a frequency which is higher than that of the highest-frequency signal component to be transmitted from any of said signal-input channels over said signal-transmission channel, and means for controlling the rate of change of charge of said condenser to decrease the rate of scanning only during the period a signal-input channel which is in use is connected to

said signal-transmission channel, whereby the fraction of an operating cycle of said first-named means that any particular signal-input channel which is in use and its corresponding signal-output channel are connected together through said signal-transmission channel is controlled inversely in accordance with the number of signal-input channels which are in use during said operating cycle.

9. A multiplex signal-translating system comprising, a signal-transmission channel, a plurality of signal-input channels, a plurality of corresponding signal-output channels, a cathode-ray tube adapted to be connected with said signal-input channels, a cathode-ray tube adapted to be connected with said signal-output channels, means including said cathode-ray tubes and means for synchronously scanning said tubes, comprising a condenser and means for charging and discharging said condenser, for cyclically simultaneously connecting and simultaneously disconnecting said signal-input channels and corresponding signal-output channels to said signal-transmission channel in a predetermined sequence and at a frequency which is higher than that of the highest-frequency signal component to be transmitted from any of said signal-input channels over said signal-transmission channel, and means for controlling the rate of change of charge of said condenser to decrease the rate of scanning only during the period a signal-input channel which is in use is connected to said signal-transmission channel, whereby the fraction of an operating cycle of said first-named means that any particular signal-input channel which is in use and its corresponding signal-output channel are connected together through said signal-transmission channel is controlled inversely in accordance with the number of signal-input channels which are in use during said operating cycle.

10. A multiplex signal-translating system comprising, a signal-transmission channel, a plurality of signal-input channels, a plurality of corresponding signal-output channels, means for cyclically simultaneously connecting and simultaneously disconnecting said signal-input channels and corresponding signal-output channels to said signal-transmission channel in a predetermined sequence and at a frequency which is higher than that of the highest-frequency signal component to be transmitted from any of said signal-input channels over said signal-transmission channel, and means responsive to a control derived from channels in use for maintaining the time of each operating cycle of said first-named means substantially constant during periods when any of said channels are in use and for controlling the fraction of an operating cycle of said first-named means that any particular signal-input channel which is in use and its corresponding signal-output channel are connected together through said signal-transmission channel inversely in accordance with the number of signal-input channels which are in use during said operating cycle.

11. A multiplex signal-translating system comprising, a signal-transmission channel, a plurality of signal-input channels, a plurality of corresponding signal-output channels, a cathode-ray tube adapted to be connected with said signal-input channels, a cathode-ray tube adapted to be connected with said signal-output channels, means, including said cathode-ray tubes and means for synchronously scanning said tubes,

for cyclically simultaneously connecting and simultaneously disconnecting said input channels and corresponding signal-output channels to said signal-transmission channel in a predetermined sequence and at a frequency which is higher than that of the highest-frequency signal component to be transmitted from any of said signal-input channels over said signal-transmission channels, means responsive to a control derived from channels in use for instantaneously retarding the rate of scanning, only during the period said tubes are operative to connect a signal-input channel which is in use with said signal-transmission channel, whereby the fraction of an operating cycle of said first-named means that any particular signal-input channel which is in use and its corresponding signal-output channel are connected together through said signal-transmission channel is controlled inversely in accordance with the number of signal-input channels which are energized during said operating cycle, and means responsive to the total number of signal-input channels in use for maintaining the average rate of scanning said cathode-ray tubes substantially constant when any of said channels are in use.

12. A multiplex signal-translating system comprising, a signal-transmission channel, a plurality of signal-input channels, a plurality of corresponding signal-output channels, a cathode-ray tube adapted to be connected with said signal-input channels, a cathode-ray tube adapted to be connected with said signal-output channels, means, including said cathode-ray tubes and means for synchronously scanning said tubes, for cyclically simultaneously connecting and simultaneously disconnecting said signal-input channels and corresponding signal-output

- channels to said signal-transmission channel in a predetermined sequence and at a frequency which is higher than that of the highest-frequency signal component to be transmitted from any of said signal-input channels over said signal-transmission channel, and means for extending the time of each operating cycle of said first-named means in accordance with the number of signal-input channels which are in use and for controlling the fraction of an operating cycle that any particular signal-input channel which is in use and its corresponding signal-output channel are connected together through said signal-transmission channel inversely in accordance with the number of signal-input channels which are in use during said operating cycle.
13. A multiplex signal-translating system comprising, a signal-transmission channel, a plurality of signal-input channels, a plurality of corresponding signal-output channels, means for cyclically simultaneously connecting and simultaneously disconnecting said signal-input channels and corresponding signal-output channels to said signal-transmission channel in a predetermined sequence and at a frequency which is higher than that of the highest-frequency signal component to be transmitted from any of said signal-input channels over said signal-transmission channel, and means for controlling said first-named means to cause only the particular signal-input channels and their corresponding signal-output channels which are in use during an operating cycle of said first-named means to be connected together simultaneously and to share the effective portion of said operating cycle.

JOHN C. WILSON.
